UNITED STATES PATENT OFFICE.

LESLIE H. BURLIN, OF CHICAGO, ILLINOIS, ASSIGNOR TO BURLIN CO., A FIRM COMPOSED OF LESLIE H. BURLIN AND WALTER H. SEDGWICK, OF CHICAGO, ILLINOIS.

DESIGN FOR A BRACKET FOR BRIDGE LAMPS OR SIMILAR ARTICLE.

Application filed October 10, 1925. Serial No. 15,095. Term of patent 7 years.

To all whom it may concern:

Be it known that I, LESLIE H. BURLIN, a citizen of the United States of America, residing at Chicago, in the county of Cook and State of Illinois, have invented a new, original, and ornamental Design for a Bracket for Bridge Lamps or Similar Article, of which the following is a specification, reference being had to the accompanying drawing forming a part thereof.

The Fig. 1, is a plan view and Fig. 2, an inverted plan of a bracket for bridge lamps or similar article, showing my new design.

My bracket for bridge lamps or similar article is made and sold as a complete and separate article of manufacture.

I claim:

The ornamental design for a bracket for bridge lamps or similar article, as shown.

LESLIE H. BURLIN.
